CHECK DRAFT DAMPER AND SOOT ELIMINATOR FOR HEATERS

Filed Oct. 10, 1929

Inventor:

Donald B. Tolley

By *Albert Scheibl*
Attorney.

UNITED STATES PATENT OFFICE

DONALD B. TOLLEY, OF MACOMB, ILLINOIS, ASSIGNOR TO AMERICAN STEEL PRODUCTS CO., OF MACOMB, ILLINOIS, A CORPORATION OF ILLINOIS

CHECK-DRAFT DAMPER AND SOOT ELIMINATOR FOR HEATERS

Application filed October 10, 1929. Serial No. 398,770.

My invention relates to the type of heaters in which a by-pass duct leads from the ash-pit to the flue, and in which this duct is provided both with an air inlet and with dampers respectively controlling the air inlet and the portion of the duct between this inlet and the flue.

Heaters of this type have heretofore been provided with two conjointly acting (and sometimes integral) dampers for the above mentioned purposes. In such heater constructions, the duct-controlling damper is desirably pivoted at its lower end to the outward wall of the duct, so as to swing upwardly toward the inner face of that wall when this damper is opened. Thus arranged, the duct-controlling damper, when only partly open, slopes upwardly away from the duct wall to which it is pivoted, thereby affording a trough adapted to catch both soot from the flue and coal which may accidentally have spilled into the check-draft chamber when the fuel for the heater was replenished. The coal or soot which is so caught between the damper and the pivoting flue wall is apt to block a wider opening of the same damper; and when this flue-controlling damper is rigidly connected to the inlet-controlling damper, such an action of the coal or soot will also prevent the latter damper from closing the air inlet properly, so that the control arrangement can no longer function adequately.

In its general objects, my invention aims to overcome these objections by providing an auxiliary and movable discharge flap in the by-pass duct wall which will be opened automatically whenever the duct-controlling damper is moved to a position in which the cut is widely open, so that any accumulations on the outer or upward face of the duct-controlling damper can drop out through a duct-opening which is closed by the said flap when the same damper is in a duct-choking position.

Moreover, my invention aims to provide a simple and inexpensive arrangement for this purpose, and one in which gravity always tends to return both the dampers and the discharge flap to certain positions. Still fur-

ther and also more detailed objects will appear from the following specification and from the accompanying drawings, in which—

Fig. 1 is a fragmentary vertical section through a coal-burning heater embodying my invention, showing the two dampers and the discharge flap in the positions which they occupy when the heater is relatively cool. 55

Fig. 2 is a section similar to a portion of Fig. 1 but with the two dampers and the discharge flap in their other extreme positions, as occupied when the heater is unduly hot. 60

Fig. 3 is a section along the line 3—3 of Fig. 1. 65

Fig. 4 is an exterior elevation of the twin damper unit and the adjacent duct portions, drawn on a smaller scale than Figs. 1 to 3.

In Fig. 1, the body of the heater is provided along one of its exterior walls 1 with a by-pass duct 2 leading from the ashpit 3 to a check-draft chamber 4 underhanging the flue collar 5, this chamber being connected to the combustion chamber 6 of the heater by suitable passages (such as an aperture 7) through which the combustion gases can pass from the combustion chamber to the flue 8. 70 75

The by-pass duct 2 is provided intermediate of its length, and desirably in its outward wall 9, with an opening 10, and a pivot shaft 11 extends across this opening parallel to the said outward wall at a considerable distance from both the upper and lower edges of the said opening. Pivoted on the pivot shaft 11 is a damper member comprising a duct damper 12 adapted to extend substantially across the bore of the by-pass duct, and an inlet damper 13 adapted to close the portion of the opening 10 which is below the pivot shaft. Then I also provide a separate flap 14 pivoted to the same duct wall 9 adjacent to the upper edge of the said opening 10, which flap swings downward by gravity and is adapted to close the part of the said opening above the pivot shaft. 80 85 90

Where the damper arrangement is to be automatically controlled in response to the temperature of the space in which the heater is used, as for example when it is used in a brooder, I make the upper or duct damper 12 95 100

heavier than the inlet damper 13, and desirably provide a weight 15 extending inwardly from the inner face of the duct damper 12 to make the latter overbalance the combined weight of the inlet damper, the connecting link 16, and the lever 17 which is actuated thermostatically. For such actuation, I am here showing a thermally expansible wafer 18 interposed between this lever and a rigid bracket 19 extending outwardly from the by-pass duct.

Then I also provide one of the members 12 and 14 with a nub 20 projecting toward the other of these members for affording a minimum spacing between them, desirably by casting such a nub on the outer face of the duct damper 12.

With my draft control thus arranged, the excessive weight of the weighted duct damper 12 causes the latter to extend substantially across the by-pass duct when the heater is relatively cool, as shown in Fig. 2, thus closing the by-pass from the ashpit to the flue. In this position, the inlet damper 13 extends away from the lower part of the opening 10, thus permitting air to enter the duct below the duct damper 12 and to pass downwardly into the ashpit 3 below the grate 21, so as to produce a down-draft for air supply through the grate.

When the temperature of the heater increases, the expansion of the thermostatic wafer 18 depresses the lever 17 (which is pivoted on a suspending bolt 22) and acts through the connecting link 16 to rock the damper member in a direction which is counterclockwise in Figs. 1 and 2, thereby gradually closing the inlet damper 13 and swinging the duct damper 12 away from the heater wall 1.

As soon as this swinging causes the nub 20 to engage the flap 14, the further movement of the duct damper in the aforesaid direction causes this flap to swing open, and the combined movements of the two dampers and the flap continues until the damper member is halted by a suitably disposed stop, as for example by having the inlet damper 13 engage the outer duct wall 9 as shown in Fig. 1.

When the heater is relatively cool, so that the parts are in the positions shown in Fig. 2, or in positions intermediate between those of Figs. 1 and 2, soot from the flue may drop down the by-pass duct and lodge on the upper face of the duct damper. So also, if coal is spilled into the check draft chamber when the heater is refueled through its top, such coal may roll down upon the duct damper, where it would be apt to prevent an opening movement of the latter if the discharge flap 13 were not provided.

However, by providing this flap, and by further providing the spacer nub 20, I cause the said flap to swing ahead of the duct damper when this is approaching a nearly

vertical position adjacent to the outer duct wall 9. Consequently, any such collected soot or fuel is automatically discharged from the by-pass duct whenever the duct damper opens. Furthermore, the positive spacing of the discharge flap for a minimum distance from the duct damper 12 by the nub 20 prevents sticky flue drips from gumming this damper to the outer duct wall 9, so that I avoid the heretofore encountered interference with the free operation of such by-pass dampers.

However, while I have heretofore described my invention in connection with a brooder heater, I do not wish to be limited as to its application. Nor do I wish to be limited to the above disclosed details of construction and arrangement, since changes might obviously be made without departing either from the spirit of my invention or from the appended claims. For example, the check-draft chamber in the illustrated embodiment may effectively be considered as a part of the flue of the heater, and the by-pass duct as extending effectively from the ashpit to the flue.

With some heater constructions and fuels, the spacing projection 20 might be omitted, although I preferably provide such a spacer to insure a positive discharge passage between the duct damper and the flap.

I claim as my invention:

1. The combination with a heater having a by-pass duct extending from its ashpit to its flue, the said duct having an air inlet opening intermediate its height, of an inlet damper controlling the admission of air through the lower part of the said opening, a duct damper controlling the duct above the inlet damper, and a flap above the inlet damper for controlling the upper part of the said opening, the flap being movable by gravity to its closure position and movable by one of the said dampers to its open position.

2. The combination with a heater having a by-pass duct extending from its ashpit to its flue, the said duct having an air inlet opening intermediate its height, of an inlet damper controlling the admission of air through the lower part of the said opening, a duct damper controlling the duct above the inlet damper, and a flap above the inlet damper for controlling the upper part of the said opening, the flap being movable by gravity to its closure position and movable by the duct damper to its open position.

3. The combination with a heater having a by-pass duct extending from its ashpit to its flue, the said duct having an air inlet opening intermediate its height, of an inlet damper controlling the admission of air through the lower part of the said opening, a duct damper controlling the duct above the inlet damper, and flap pivoted at its upper edge to the duct and controlling the upper part of the said opening, the duct damper being piv-

oted to the duct below the pivoting of the said flap and being disposed for opening the flap during the opening movement of the duct damper.

5. A heater construction as per claim 1, including means for affording a minimum spacing between the duct damper and the said flap.

10. A heater construction as per claim 2, in which the duct damper swings upwards towards the flap during its opening movement, and in which one of the last named two elements has a projection directed toward the other element for affording a minimum spacing therebetween when the duct damper is wide open.

15. A heater construction as per claim 2, in which the duct damper extends at an acute angle to the flap when both thereof are in 20 their closure positions, and in which the duct damper has a projection on its upper face disposed for engaging the said flap before the duct damper reaches its wide open position during the opening movement of the duct 25 damper.

7. In a heater having a by-pass duct extending from its ashpit to its flue and having an air inlet opening in an outer wall of the duct, a unitary double damper member piv- 30 oted intermediate of its height to the duct on a horizontal axis intermediate of the height of the said opening; the damper member comprising in rigidly connected formation a duct damper disposed within the duct and extend- 35 ing upwardly from the said axis when the duct damper is open, and an inlet damper depending from the said axis and disposed outside the duct and adapted to engage the outer face of the duct; a flap pivoted to and 40 depending exteriorly of the duct from a pivot axis adjacent to the upper edge of the said opening; and a spacer interposed between the duct damper and the flap and carried by one 45 thereof for causing the flap to swing outwardly when the duct damper is approaching the end of its duct opening movement.

Signed at Macomb, Illinois, September 30th, 1929.

DONALD B. TOLLEY.
